“CBRIX—Batena compacta de iones de litio”, first published Oct. 1, 2020. Micropower Group [<https://es.micropower-group.com/micropower-group/cbrix-bateria-compacta-de-iones-de-litio/>] (Year: 2020).*Primary Examiner — Rosemary K Tarcza*Assistant Examiner* — Seth David Kumpf(74) *Attorney, Agent, or Firm* — Ballard Spahr LLP(57) **CLAIM**

The ornamental design for a battery, as shown and described.

DESCRIPTION

FIG. 1 is a top perspective view of a first embodiment of a battery showing our new design;

FIG. 2 is a front elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a top perspective view of a second embodiment of a battery showing our new design;

FIG. 8 is a front elevational view thereof;

FIG. 9 is a left side elevational view thereof;

FIG. 10 is a right side elevational view thereof;

FIG. 11 is a top plan view thereof; and,

FIG. 12 is a bottom plan view thereof.

In the drawings, the broken lines depict environmental subject matter only and form no part of the claim.
